ACTIVATION AND REACTIVATION OF ELECTRON EMISSION TUBES

Application filed October 29, 1929. Serial No. 403,218.

This invention relates to electron emission tubes, and more particularly to a method of activating or reactivating tubes having oxide coated cathodes so as to improve the electron emission thereof.

Even though tubes are mechanically similar and undergo identical manufacturing processes large variations are found in the performance of the resulting tubes. Some newly manufactured tubes do not have sufficient emission to pass test, and some tubes have only a very short life. Even the average normal tube has a relatively limited life, say 1000 operating hours, after which it is useless because of reduced cathode emission.

The primary object of our invention is to provide a simple, speedy, and economical method of reactivating used tubes which are no longer satisfactory, particularly due to reduced emission. This we have found to be possible simply by high internal bombardment.

When the tube has a grid the latter may be overheated owing to its small radiating area, and accordingly a further object of our invention is to apportion the relative heating of the grid and anode so as to prevent overheating of the grid relative to the heating of the anode. Another object of our invention is to provide the desired heating of the tube elements without excessive accompanying electron emission and/or ionization currents which may prove injurious to the tube cathode. A still further object of our invention is to prevent overheating of the tube elements which might cause vaporization of nickel within the tube, and which, if carried still further, might actually destroy the tube elements.

Still another object of our invention is to transfer gas which may be present in the tube electrodes from them to the tube envelope and getter material. A still further object of our invention resides in the provision of a circuit arrangement for the practice of the method of our invention.

To the accomplishment of the foregoing and such other objects as will hereinafter appear, our invention consists in the method steps and their relation one to the other as herein-

after are more particularly described in the specification and sought to be defined in the claims. The specification is accompanied by a drawing showing a schematic wiring diagram of a circuit suitable for the practice of 55 our invention.

Referring to the drawing, a tube to be reactivated, 2, has its cathode 4 connected with a source of cathode heating current 6. A variable resistor 8 may be connected in circuit for varying the cathode temperature, and a volt meter 10 used to indicate the terminal potential applied to the cathode. The tube anode 12 may be connected through a switch 14 to a source of relatively high positive 65 anode potential 16. The value of this potential is not at all critical and may be varied over wide limits, but should be at least equal to the operating potential normally used with tube. In the case of heater type tubes the 70 heater may be connected in circuit as shown, but the negative terminal of the source 16 is connected to the cathode emitter itself. With heater type tubes direct current as from a battery may be used to heat the cathode, the 75 transformer being especially preferred for directly heated cathodes because during reactivation the plate current is very high, and without the equalization permitted by the center tap and the use of alternating current 80 the cathode would be very unequally heated along its length.

In accordance with our invention the cathode 4 is heated to a temperature substantially above normal, equivalent to the temperature 85 corresponding to say a 50% increase above normal in cathode terminal potential, and at the same time the anode potential is applied to the tube.

The theory behind this method of reactivating the tube cathode is not certain, but may possibly be explained as follows. During the high internal bombardment which we apply to the tube gas present in the tube is ionized by the electron stream from the cathode, and the positive ions thereof bombard the cathode. The gas to be ionized may be released from the plate by the high velocity electron bombardment, and thereafter ionized. The positive ions hit the cathode with 95 100

a high velocity, and probably form a layer of positive ions on the surface thereof, which layer acts to reduce the space charge at the surface so that the electron stream may more readily flow out of the cathode.

5 Another effect which may be present is the building up of a supply of the metal barium by electrolytic formation, the barium making the cathode an improved electron emitter. Barium is originally formed in the cathode when the tubes are manufactured, but this supply of barium is gradually diminished during the use of the tube, inasmuch as the rate of formation of barium during the 10 normal use is probably less than the rate of exhaustion thereof. Our reactivation process probably again forms a supply of barium sufficient to make up for a gradual loss thereof over a long period of time, and probably 15 also increases the rate of formation of barium during use.

If the tube 2 has a grid, indicated at 18, this should be polarized in order to help obtain the desired cathode emission. The grid 20 may, for example, be connected directly to the anode and both elements treated as a common anode. This, however, is open to the fault that the grid will ordinarily be overheated relative to the heating of the anode, 25 owing to the very much smaller radiating surface of the grid. It is therefore desirable to apportion the heating of the grid and plate, this we do by applying a reduced potential to the grid relative to the potential 30 applied to the plate. This may be done by connecting a battery or other suitable source of potential between the grid and plate. However, there is an advantage in having the grid initially polarized to a high potential 35 in order to help start the electron emission from the cathode, and for this reason, as well as for the sake of simplicity of apparatus, we prefer to obtain the desired reduction 40 in grid potential by connecting a resistance between the grid and plate. In this manner the grid is initially polarized at the anode potential, but after space current begins to flow the grid potential is reduced and the reduction thereof is varied in accordance 45 with the grid current flow, so that the potential and the heating of the grid are automatically regulated.

If a high resistance is connected between the grid and plate the grid potential is apt 50 to be reduced too quickly when space current begins to flow, so that the cathode emission does not have time to get well under way. We have found that it is desirable to use a 55 resistance between the grid and plate having a high positive temperature coefficient of resistance. Such a resistance will remain relatively low in value until sufficient time has elapsed for it to be heated up, and in this 60 period the cathode emission may develop to the desired point. We find that a tungsten

filament lamp forms a suitable resistance for this purpose, such a lamp being indicated in the drawing by the lamp 20 connected between the grid 18 and the plate 12. With tubes having say one square centimeter of cathode area and four square centimeters of anode area and an amplification constant of 12 we find that a 120 volt tungsten lamp rating between 10 and 25 watts may be used for the resistor 20.

75 The reduction in grid potential has an additional advantage because of the resulting increase in tube impedance. What is desired is a high anode temperature, and the temperature obtainable depends upon the power 80 dissipated, which varies as the product of the current and the potential. It is not desirable to have an excessive space current, for that may injure the cathode, and it is therefore necessary to apply a high anode potential. The 85 aforesaid reduction in grid potential increases the tube impedance and makes it possible to increase the anode potential while decreasing the space current, so as to obtain a desired heating effect without an excessive 90 electron drain on the tube cathode. Differently expressed, the electron flow is reduced, but the impact velocity on the anode is increased.

95 It was before stated that the automatic regulation of grid potential apportions the heating the grid relative to the heating of the anode. It is further necessary to limit the overall heating of the bombarded tube elements, for if overheated, nickel contained therein may be vaporized and deposited upon the tube cathode, thereby spoiling the emissivity thereof. Vaporization of nickel may be detected by a dark deposit of nickel on the relatively white oxide-coated cathode of the tube, and also by a darkening of the tube envelope due to a deposit of nickel on the inside wall thereof. The cathode too may contain nickel, particularly in the heater type tubes, which usually use a nickel sleeve around the heater. Heat radiated from the bombarded grid and anode is added to the normal cathode heat, and this may cause release of nickel vapor from the cathode itself. Nickel vapor from any of the tube elements deposited upon the cathode lowers its emission, and it is therefore necessary to prevent heat sufficient to vaporize nickel, as well as still more excessive heating of the tube elements such as might physically destroy the same.

100 105 110 115 120 125 120 For regulating the space current through the tube we find it desirable to insert in series with the electrodes being bombarded a resistance, here exemplified by a tungsten filament lamp 22, having a high positive temperature coefficient of resistance. This acts as a ballast lamp and provides automatic regulation of the anode potential and consequently of the space current so as to keep the

latter within the desired limits. For tubes such as were already mentioned, having an anode area of say 4 square centimeters, the space current should be limited to approximately 250 milli-amperes per square centimeter of cathode area. For this purpose the lamp 22 may be a 120 volt 100 watt tungsten filament lamp. If the electrodes are made of a metal such as molybdenum or tungsten the current limitation may be increased to say 300 or 400 milli-amperes per square centimeter of cathode area without vaporization of these metals, and consequent injurious coating of the cathode.

At the beginning of the reactivation of the tube it may prove desirable in the case of tubes which are very "gassy" to further limit the space current for a period of say half a minute, though we may mention at this point that a very "gassy" tube may not be worth saving unless special precautions are taken for the reduction of this gas content. The current limitation is desirable because ionization of the gas in the tube may permit an excessively large space current injurious to the tube cathode. With such tubes the space current should be held down to say 100 milli-amperes per square centimeter of cathode area, and for this purpose a higher resistance 25 may be connected in the anode circuit. In the present case a 120 volt 25 watt tungsten filament lamp 24 is arranged in parallel with resistance 22 so as to be selectively connected in circuit with the tube anode. By throwing switch 14 onto contact 26 during the first part of the activation process there will be no danger of excessive space current due to ionization. A milli-ammeter 28 may be connected in the anode circuit, and if the reading thereof is sufficiently small to indicate that the lower resistance 22 may be used, the switch 14 may then be thrown to the contact 30, thereby applying anode potential to the tube through the ballast resistance 22, for the remainder of the activation process.

Switch 14 may further be used to flicker or momentarily interrupt the anode and grid potentials, if this is done manually, although it may be mechanically done by means of a 50 commutator. The flickering of resulting interruptions preferably should remove the anode and grid potentials for periods of one or two seconds at intervals of about fifteen seconds. The object of this is to permit 55 of the equivalent of removal of gas from the tube, by causing the gas to be occluded on the inner surface of the tube envelope. The reactivation heats up the tube elements sufficiently to drive off gas therefrom. This gas 60 is ionized, resulting in bombardment of the cathode by positive ions, with beneficial effects as previously explained. However, it is desirable to improve the vacuum in the tube and to avoid having gas in a distributed state 65 throughout the tube. Ionized gas is subject

to forces of ionization which make it difficult to condense the gas, whereas molecular gas is freed of ionization forces. By flickering or momentarily interrupting the said potentials periods are provided during which the gas ions may reform into molecules. These molecules do not condense readily on the tube electrodes, owing to the heated condition of the electrodes. However, the tube envelope is in a relatively cool state, and the molecular gas therefore tends to go to the walls of the tube or to the getter thereon, where it is condensed and occluded. By flickering or interrupting the said potentials, therefore, we obtain to a limited extent the equivalent of 70 pump evacuation, and the effective gas content of a tube may be considerably reduced by this method. Flickering or momentary interruption may be used from the beginning of the activation process, or, in the case of 75 tubes with heavier electrodes, may be postponed long enough for the tube elements to become heated up, after which the flickering or interruptions may be started.

The entire reactivation process may take 80 say one minute, but may be continued longer, particularly in order to obtain more flickering or intermittent periods for condensing free gas in the tube. However, a tube which is not properly reactivated in say five minutes 85 is probably too far gone to be capable of being reactivated by our process.

From the foregoing explanation it will be clear that it is undesirable to permit heating of the tube envelopes during reactivation, 90 and in fact, it is preferable to provide good air circulation around the tubes, and better still, to actually cool the tubes during the reactivation process, as by means of a fan 95 40, or more elaborate and efficient cooling 100 means.

Our process may also be applied to the activation of tubes, in contra-distinction to reactivation of tubes, that is, the activation of tubes which have not yet been used, rather 110 than used tubes. We find that our invention as aforescribed may be applied to rejected tubes which cannot pass factory test because of low cathode emission. A very large percentage of the rejects may be made operative 115 and brought up to normal by applying our activation process.

In fact, it may prove economical in some instances to apply the activation process to 120 all of the tubes being manufactured before the tubes are put under test. The tubes may then be given a uniform activation treatment for a relatively short period of time, the tubes being simultaneously activated in banks, as is indicated by the tubes shown in the wiring 125 diagram of the drawing, but the tubes preferably have individual ballast lamps, such as the lamps 20, 22, and 24, for independently regulating the grid potential and the space current of each of the tubes according to the 130

electron emission characteristic of each of the tube cathodes.

By adding this activation step subsequent to the normal tube manufacturing process the percentage of rejects may be cut down to a minimum, and the tubes need be tested only once. The tubes are given a long life at normal performance, so that the percentage of tubes which are apparently normal under test but which rapidly deteriorate in use is also greatly reduced. When using the activation step in this manner the possibility of issuing tubes which shortly thereafter become "gassy" due to gas occluded in the tube electrodes is obviated because during the activation step the bombardment of the electrodes drives gas therefrom, which if small will be removed by condensation of gas on the tube envelope, but which if large will make the tube initially "gassy" so that it will be rejected and not issued into service.

It will be apparent that while we have shown and described our invention in the preferred form, many changes and modifications may be made in the method disclosed without departing from the spirit of the invention, defined in the following claims.

We claim:

1. The method of activating electron emission tubes which includes increasing the cathode temperature substantially above normal, applying a high positive anode potential, and holding the space current within a desired limit depending upon the radiating surface of the anode in order to prevent overheating thereof.

2. The method of activating electron emission tubes which includes increasing the cathode temperature substantially above normal and applying a high positive anode potential, and momentarily interrupting the space current by occasionally momentarily interrupting the anode potential.

3. The method of activating electron emission tubes which includes increasing the cathode temperature substantially above normal and applying a high positive anode potential, momentarily interrupting the space current by occasionally momentarily interrupting the anode potential, and simultaneously cooling the envelope of the tube.

4. The method of activating electron emission tubes which includes increasing the cathode temperature substantially above normal, applying a high positive anode potential, holding the space current within a desired limit depending upon the radiating surface of the anode, and momentarily interrupting the space current by occasionally momentarily interrupting the anode potential.

5. The method of activating electron emission tubes which includes increasing the cathode temperature substantially above normal, applying a high positive anode potential,

holding the space current within a desired limit depending upon the radiating surface of the anode, momentarily interrupting the space current by occasionally momentarily interrupting the anode potential, and simultaneously cooling the envelope of the tube. 70

6. The method of activating electron emission tubes which includes increasing the cathode temperature substantially above normal, applying a high positive anode potential for about one to five minutes, holding the space current below a value which would cause vaporization of nickel in the tube, and momentarily interrupting the space current by occasionally momentarily interrupting the anode 75 potential. 80

7. The method of activating electron emission tubes having a grid which includes increasing the cathode temperature substantially above normal, applying a high positive potential to the anode, and a reduced potential to the grid in order to prevent overheating of the grid relative to the anode, and holding the space current within a desired limit depending upon the radiating surface 90 of the anode in order to prevent overheating of the grid and anode. 95

8. The method of activating electron emission tubes having a grid which includes increasing the cathode temperature substantially above normal and applying a high positive potential to the anode and a reduced potential to the grid, and momentarily interrupting the space current by momentarily interrupting the anode and grid potentials. 100

9. The method of activating electron emission tubes having a grid which includes increasing the cathode temperature substantially above normal, applying a high positive potential to the anode and a reduced potential to the grid, holding the space current within a desired limit depending upon the radiating surface of the anode, and momentarily interrupting the space current by momentarily interrupting the anode and grid potentials. 105

10. The method of activating electron emission tubes having a grid which includes increasing the cathode temperature substantially above normal, applying a high positive potential to the anode and a reduced potential to the grid, holding the space current within a desired limit depending upon the radiating surface of the anode, momentarily interrupting the space current by momentarily interrupting the anode and grid potentials, and simultaneously cooling the envelope of the tube. 110

11. The method of activating electron emission tubes having a grid which includes increasing the cathode temperature substantially above normal, applying a high positive potential to the anode and a reduced potential to the grid in order to prevent overheating of the grid relative to the anode, holding the 115

- space current below a value which would cause vaporization of nickel in the tube, and momentarily interrupting the space current by momentarily interrupting the anode and grid potentials. 5
12. An arrangement for reactivating electron emission tubes comprising a source of cathode heater current, means to vary the heater current, a source of direct anode potential, means to automatically limit the space current of the tube, and means including a resistance having a high positive temperature coefficient to automatically reduce the grid potential relative to the anode potential in order to prevent overheating of the grid. 10
13. An arrangement for reactivating electron emission tubes comprising a source of cathode heater current, means to vary the heater current, a source of direct anode potential, means including a resistance having a high positive temperature coefficient to limit the space current of the tube, and means to momentarily interrupt the anode potential. 15
14. An arrangement for reactivating electron emission tubes comprising a source of cathode heater current, means to vary the heater current, a source of direct anode potential, means including a resistance having a high positive temperature coefficient to limit the space current of the tube, means to momentarily interrupt the anode potential, and means to cool the envelope of the tube. 20
15. An arrangement for reactivating electron emission tubes comprising a source of cathode heater current, means to vary the heater current, a source of direct anode potential, means to limit the space current of the tube, means to momentarily interrupt the anode potential, means connecting the grid to the source of anode potential, and means to reduce the grid potential relative to the anode potential in order to prevent overheating of the grid. 25
16. An arrangement for reactivating electron emission tubes comprising a source of cathode heater current, means to vary the heater current, a source of direct anode potential, a resistance having a high positive temperature coefficient connected in series with the anode, means to momentarily interrupt the anode potential, and means including a resistance having a high positive temperature coefficient connected between the grid and the anode of the tube in order to polarize the grid and to prevent overheating of the same. 30
17. An arrangement for reactivating electron emission tubes comprising a source of cathode heater current, means to vary the heater current, a source of direct anode potential, a resistance having a high positive temperature coefficient connected in series with the anode, means to momentarily inter- 35
- rupt the anode potential, means including a resistance having a high positive temperature coefficient connected between the grid and the anode of the tube in order to polarize the grid and to prevent overheating of the same, and means to cool the envelope of the tube. 40
18. An arrangement for reactivating electron emission tubes comprising a source of cathode heater current, means to vary the heater current, a source of direct anode potential, a plurality of resistances of different magnitude having high positive temperature coefficients, means to apply the anode potential to the tube anode selectively through either of said resistances and to permit of momentarily interrupting of the anode potential, and means including a resistance having a high positive temperature coefficient connected between the grid and the anode of the tube in order to polarize the grid and to prevent overheating of the same. 45
